(57) **CLAIM**

The ornamental design for a cycling computer, as shown and described.

DESCRIPTION

FIG. 1 is a topside perspective view of a cycling computer showing our new design.

FIG. 2 is another topside perspective view thereof with the cycling computer mounted to the front end of a bicycle.

FIG. 3 is a top plan view thereof.

FIG. 4 is a bottom plan view thereof.

FIG. 5 is a left side view thereof.

FIG. 6 is a right side view thereof.

FIG. 7 is a front elevation view thereof; and,

FIG. 8 is a back elevation view thereof.

The broken lines showing a portions of a bicycle in FIG. 2 illustrate environmental structure; all other broken lines in the drawings show portions of a cycling computer.

None of the broken lines form any part of the claimed design.
